UNITED STATES PATENT OFFICE.

LORAIN M. WILSON, OF INDIANAPOLIS, INDIANA.

SASH PULLEY.

Application filed July 18, 1924. Serial No. 726,707.

To all whom it may concern:

Be it known that I, LORAIN M. WILSON, a citizen of the United States, residing at Indianapolis, in the county of Marion and

5 State of Indiana, have invented new and useful Improvements in Sash Pulleys, of which the following is a specification.

10 My invention has reference, in its broad aspect, to improvements in anti-friction pulley devices for sash weights of the type wherein the load represented by the sash and weight is distributed between a plurality of pulleys, and more particularly it is my purpose to provide a device of this character which will not necessitate mortising of 15 the window frame to which it is applied and countersinking the pulley box as in other devices now in use, and furthermore the pulley box of my device is essentially a one-piece structure designed to be stamped and pressed from a blank of pressed steel or malleable iron thereby decreasing its initial 20 cost of manufacture and greatly adding to its strength, simplicity and durability.

25 According to my invention it is merely necessary to bore a hole directly through a window frame into which the cylindrical body of my pulley box is inserted, and by means of lateral ears through which screws 30 are engaged with the rear face of the frame my device is securely held in place against displacement. In mounting and detaching my pulley device no special tools are necessary and both operations need consume but 35 a few moments. Furthermore, I have provided unique means for reinforcing my pulley device against downward stress or drag or torsional movement induced by the load 40 of a window weight upon the overhanging portion of the box.

45 In addition to the above advantages which are attributable to my invention, and others which will hereinafter be apparent, it is also especially emphasized that in manufacturing my pulley device on the basis of quantity production there are no operations which cannot be performed by conventional machinery, such as power presses, now in general use. The blank from which my 50 box is formed is designed to be cut from a stock sheet of metal and formed in a single operation, at which time the ears are also stamped out; the pulleys are then mounted and the top meeting edges of the body braised or welded together, whereupon the 55 ends of the pulley shafts are upset to com-

plete the assembly, and it will be noted that the said pulley shafts serve also to prevent spreading or distortion of the sides of the box.

60 The structural elements employed to accomplish the above and other results and objects will be hereinafter more fully described in detail and specifically pointed out in the claims appended hereunto and forming a part 65 of this specification, but the scope of the invention may only be determined by the limits defined in the claims.

70 In the accompanying drawing, wherein is illustrated the preferred embodiment of my invention:

75 Figure 1 is a front elevation of my device.

Figure 2 is a sectional side elevation showing to advantage the relative position of the 80 pulleys.

Figure 3 is a rear view.

Figure 4 is a plan view of the blank from which my pulley box is formed, and

Figure 5 is a detail view of one of the 85 pulleys showing the ball race.

Like characters of reference refer to like or similar parts throughout the several views of the drawings.

85 With a view to imparting a clear understanding of the manner of forming my pulley device on the supposition that such an understanding will tend to the complete and accurate comprehension of its structural details and advantages, attention is invited to 90 Figure 4 of the drawing wherein the blank is shown. In forming the pulley box from the blank, the portion *a* is pressed out approximately as indicated by the shade lines to form a uniformly curved cowl having a 95 straight edge *b*, this initial operation throws the edges *c* together, and in the same operation the portions *d* are semi-cylindrically bent which disposes portions *e* substantially 100 parallel and spaced from each other. The 105 next operation, which is the final one consists in bending portions *f* to complete (in conjunction with adjacent portions *d*) a true cylinder. At any time during either of these operations the ears *g* may be stamped out 110 and the edge flanges *h* turned at right angles to the body along the dotted lines.

Referring now to the remaining figures of the drawing, the body (1) of my pulley box, which is formed as above described by 115 cylindrically shaping the portions *d* and *f* of the blank, is provided with flanges (2)

along a portion of the top meeting edges thereof, and these are brazed or welded together. Stamped out from the body (1) are opposed lateral ears (3) provided with 5 openings (4) for receiving attaching screws (not shown) adapted for engagement in the rear face of a window frame to hold the body in place. Mounted on a shaft (4^a) extending transversely through the body (1) 10 is a pulley (5), said pulley is anti-frictionally mounted by means of ball bearings (6^a) operating in a ball race (6^b) after the manner shown in Figure 5. It will be noted that the periphery of the pulley extends 15 slightly in advance of the front edge of the body.

Integrally formed on the body (1) is a cowl (7), the same being pressed from the blank shown in Figure 4 as indicated at *a* 20 thereon, and extending from the cowl are relatively parallel side portions (8) terminating in angular legs (9) each having one vertical straight edge (10) adapted to abut an adjacent window frame (not shown) to 25 reinforce my device against downward stress or drag or torsional movement. The pulley (11), which is considerably larger in diameter than the pulley (5), is mounted on a shaft (12) journaled in the side portions 30 (8), and is of the ball bearing anti-friction type shown in detail in Figure 5, with possible end play compensated for by loose washers (not shown). Each of the legs (9) may 35 be, and preferably is, provided with a lateral foot (13) which is seatable against the face of a window frame to cooperate with the legs in firmly supporting my device in position. These feet may be formed integrally with the legs and stamped out simultaneously with the legs, or they may be 40 brazed upon the legs.

In operation, a hole of suitable size is bored directly through a window frame and the body (1) of my pulley box arranged 45 therein with the smaller of the two pulleys, designated (5), carrying the load represented by the window sash. In this position the ears (3) are seated upon the rear face of the frame with the legs (9) depending from 50 the cowl and seatable with the feet (13) against the frame. The larger of the two pulleys, designated (11), overhangs the sash weight shaft and carries the load represented by the sash weight; the downward stress 55 or drag or torsional movement being taken up or compensated for by the legs (9). Attention is especially invited to the fact that considerable variation in the configuration 60 of the pulley box can be indulged in without departing from the concept exemplified by

the particular development of the blank and the manner of pressing or stamping out the pulley box, as for instance, the sides of the cowl can be brought considerably closer together to decrease the shaft or axle span of 65 the larger of the two pulleys thereby eliminating the necessity of employing loose washers for taking up end play.

While in the foregoing, there has been illustrated and described such combination 70 and arrangement of elements as constitute the preferred embodiment of my invention, it is nevertheless desired to emphasize the fact that interpretation of the invention should only be conclusive when made in the 75 light of the subjoined claims.

Having described my invention and its objects with such attention to detail as will thoroughly acquaint one skilled in the art 80 with its construction and advantages, I claim:—

1. A pulley device comprising a one piece housing, an integral element of said housing being bent to form a cowl, semi-cylindrical extensions formed on the integral element 85 constituting the cowl and arranged with their respective upper and lower edges in abutment to provide a cylindrical body, the respective upper edges of said semi-cylindrical extensions being flanged intermediate the 90 ends of said extensions and said flanges being joined to reinforce the body, a pulley carried in the body, a pulley carried in the cowl with its axis of rotation above the lower abutting edges of the semi-cylindrical extensions and below the axis of rotation of the pulley carried by the body, and relatively 95 parallel depending members formed on the cowl, the lower edges of said depending members being inclined with respect to the longitudinal axis of the body, and the forward edges of said members being arranged 100 in a vertical plane and at right angles to the longitudinal axis of the body for the purpose set forth.

2. An article of manufacture for use in the making of boxings for pulley devices comprising a sheet metal blank formed with relatively angularly disposed sections converging to an unbroken portion having one straight edge and an edge portion on either side thereof diverging from the straight edge, the material at the points of intersection of the diverging edges with the outer edges of the angularly disposed sections being slit for the purpose defined.

In testimony whereof I affix my signature hereunto.

LORAIN M. WILSON.
